UNITED STATES PATENT OFFICE.

GUSTAV H. W. SIMMON, OF ST. LOUIS, MISSOURI, ASSIGNOR TO J. F. VOGT
& BROTHER, OF SAME PLACE.

BARREL LEVELING AND TRUSSING MACHINE.

SPECIFICATION forming part of Letters Patent No. 336,760, dated February 23, 1886.

Application filed November 2, 1885. Serial No. 181,651. (No model.)

To all whom it may concern:

Be it known that I, GUSTAV H. W. SIMMON, of St. Louis, Missouri, have invented a new and Improved Barrel Leveling and Trussing Machine, of which the following is a full, clear, and exact description.

The object of my invention is to provide a new and improved machine for leveling and trussing barrels, kegs, &c., in a single operation, which machine is simple in construction, strong and durable, and operates rapidly.

The invention consists in the construction and combination of parts and details, as will be fully described and set forth hereinafter, and pointed out in the claims.

Reference is to be had to the accompanying drawings, forming part of this specification, in which similar letters of reference indicate corresponding parts in all the figures.

Figure 1 is a front view of my improved barrel leveling and trussing machine. Fig. 2 is a side view of the same. Fig. 3 is a sectional plan view on the line $x-x$, Fig. 1. Fig. 4 is a sectional plan view on the line $y-y$, Fig. 1. Fig. 5 is a top view of the machine. Fig. 6 is a sectional plan view of the frame of the machine. Figs. 7 and 8 are end views of the compound levers. Fig. 9 is a diagrammatic view of the cam.

The bottom plate, A, and the top plate, B, are united by the four corner-rods, C. Plates or platforms D and D', united by the bars or upright pieces E, are mounted to slide vertically on the corner-rods C, and the plates F and F', also united by the upright pieces E, are held to slide vertically at the bottom of the frame formed by the four upright rods C. Screws G, mounted to revolve in the top plate, B, are passed through nuts H in the plate D, and on the upper ends of the said screws the bevel cog-wheels H' are mounted, which engage with bevel cog-wheels I on a shaft, I', having a hand-wheel, I'.

The plate F is connected by connecting-bars J, pivoted to the under side of the same, with a crank-shaft, J', journaled in the base of the machine, and provided with a worm-wheel, K, engaging with a worm, K', on a shaft, K'', provided with the belt-pulley L', over which a belt, L, passes, which also passes over the belt-

pulley L² on the shaft M, journaled in the frame N, pivoted to the top plate of the machine, and connected by the rod O with the foot-lever P or treadle, which is mounted rigidly on the shaft m, journaled in lugs on the standards in which the shaft K² is journaled, which shaft is provided with an arm; n, on the end of which a roller, o, is mounted, which runs on a cam-ring, p, projecting from the face of the worm-wheel K. The shape of the edge of the cam-ring p is shown in detail in Fig. 9.

A belt-pulley, M', is mounted on the shaft M. In the centers of the plates F and F' a shaft, Q, is mounted to slide vertically, and on the upper end of the same the leveling-disk R is formed or secured, which has a bevel edge to fit the ends of the staves, and a laterally projecting ledge, R'. The shaft Q is connected by links S' with the lever S, pivoted on a connecting-piece, E, and having its outer end connected with a screw-rod, T, passed through the end of said lever S, and having its upper end connected with an angle-lever, U, pivoted on the plate F, and having an arm, V, carrying the weight W. A leveling-disk, R, is mounted in the same manner in the upper plates, D D', with the exception that the connecting-levers, &c., are slightly different, as shown in Figs. 7 and 8.

The weights W can easily be adjusted so as to have more or less power, as circumstances may require. The platforms or plates D F have the four slots a extending from the center to the four corners, and through each slot a bolt, d, is passed, which is also passed through a segmental hoop-driver, g, which hoop-drivers have the upwardly-projecting flanges h, which act on those edges of the hoops nearest the ends of the barrel.

The operation is as follows: The drivers g are adjusted according to the size of the barrel to be leveled and trussed, and the barrel is then placed between the disks R, the end hoops being on the barrel. If the barrel also has bilge-hoops, the same are driven up tight enough to keep the staves from springing before operating on the barrel. When all parts are in place, the treadle P is pressed down, and thereby the frame N is swung up, and the belt L is tightened, thus causing the worm-

shaft K' to revolve, whereby the worm-wheel K and the shaft J' are revolved, and by means of the bars J the plate F is pressed upward, and the disks R are forced against the ends of the staves, which are thus leveled. The disks, being subjected to the pressure on the ends of the barrels, are moved relatively from each other, and the weights are swung up more or less, and by their action the ends of the staves are held level. The plates F continue to move upward, and the drivers g then act on the truss-hoops and drive them home. During this part of the operation the treadle is pressed down by the foot, and the belt is thus tightened, and when the treadle is pressed down the roller o is clear of the cam-ring p, and does not act on it. As soon as the treadle is released, the roller on the arm n swings against the cam, which presses said arm outward, and thereby the rod O is pressed up, and the belt is kept tightened by the cam, thus permitting the operator to leave the machine and prepare a fresh barrel, or to put the same in position for placing it on the machine. Half of the revolution is thus made under the control of the operator, and the other half of the revolution is controlled automatically by the cam on the crank-shaft. When the barrel has been completed, it is removed and replaced by another.

In some barrels the diameters of the heads are not alike, and in such cases the end hoops of the barrel will not be trussed the same distance, but the slack or smaller end will have the hoops driven on farther than the full or larger end; but when the ends of the barrel are of like diameter the end hoops should be driven on or trussed the same distance.

Before the machine is in operation, and when there is no barrel between the leveling-disks, both disks stand out ahead of the drivers.

The weights W, acting on the levelers, are made adjustable, so as to adjust the machine to barrels of different sizes.

Having thus fully described my invention, I claim as new and desire to secure by Letters Patent—

1. In a barrel leveling and trussing machine, the combination, with a frame, of a stationary platform, a movable platform, a movable leveling-disk held on each platform, and a lever pivoted on each platform and carrying a weight, and pivoted arms and rods connected with the weighted lever and with the movable leveling-disks, substantially as and for the purpose set forth.

2. In a barrel leveling and trussing machine, the combination, with a frame, of a stationary platform and a movable platform, a movable leveling-disk held on each platform, a weighted lever pivoted on each platform, and pivoted arms and rods, said rods connecting adjustably with said arms, substantially as and for the purpose set forth.

3. In a barrel leveling and trussing machine, the combination, with a frame, of a stationary

platform and a movable platform, a crank-shaft and connecting-rods for moving the movable platform toward and from the stationary platform, a movable leveling-disk held on each platform, a lever pivoted on each platform and carrying a weight, pivoted arms and rods connected with the weighted arm and with the movable leveling-disks, and of hoop-drivers on the platforms, substantially as herein shown and described. 75

4. In a barrel leveling and trussing machine, the combination, with a frame, of a stationary platform and a movable platform, a barrel-leveling disk in each platform, a lever, S, pivoted on each platform, links connecting said levers S with the leveling-disks, the angle-levers U, pivoted on the platforms, the rods T, connecting the same with the levers S, weights W on arms V of the levers U, and of hoop-drivers on the platforms, substantially as herein shown and described. 80 85

5. In a barrel leveling and trussing machine, the combination, with a vertical frame, of a stationary platform on the same and a movable platform mounted to move toward and from the stationary platform, a crank-shaft connected with the movable platform by connecting-bars, gearing for revolving the crank-shaft, a driving-belt for operating said gearing, a swinging frame on the top of the upright main-frame of the machine, a driving-pulley in said swinging frame, over which driving-pulley the driving belt that operates the gearing of the movable platform passes, 90 and a rod connecting the swinging frame with a treadle at the base of the machine, substantially as herein shown and described. 95 100

6. In a barrel leveling and trussing machine, the combination, with a stationary plate or platform and a movable plate or platform which can be moved toward the stationary platform, of a crank-shaft and connecting-rods for moving the adjustable platform, and a worm-wheel on the end of the crank-shaft, 105 a worm engaging with said worm-wheel, a belt-pulley on the shaft carrying the worm, a cam-ring on the end of the crank-shaft, a rocking lever on which the cam acts, a foot-lever mounted on the rocking lever, a rod connected 115 with the foot-lever, a swinging frame on the top of the machine, which swinging frame is connected with a rod connected to the foot-lever, a belt-pulley in the swinging frame, and a belt passed over the pulley in the swinging 120 frame and over the pulley on the shaft carrying the worm, substantially as herein shown and described.

7. In a barrel leveling and trussing machine, the combination, with a vertical frame, of a stationary platform on the same and a movable platform mounted to move toward and from the stationary platform, a crank-shaft for reciprocating the movable platform, a cam on the crank-shaft, and a belt-tightening device operated from said cam, substantially as herein shown and described. 125 130

8. In a barrel leveling and trussing machine, the combination, with a stationary and a movable platform, each having diagonal slots, of hoop-drivers placed on the platforms and held in the desired positions by bolts passed through the above-mentioned slots, movable barrel-leveling disks held on the platforms, and of

weights acting on the said leveling-disks, substantially as herein shown and described.
